PACKAGED UMBRELLA

Heinz Seelig, Solingen, Germany, assignor to Telesco
Brophey Limited, Montreal, Quebec, Canada

Filed Aug. 14, 1969, Ser. No. 18,681
Claims priority, application Germany Feb. 14, 1969

Term of patent 14 years

Int. Cl. D3—03

U.S. Cl. D87—1

FIG. 1

FIG. 4

FIG. 5

FIG. 3

FIG. 1 is a perspective view of the packaged umbrella;
FIG. 2 is a plan view of the packaged umbrella;
FIG. 3 is a side elevation view of the packaged umbrella;

FIG. 4 is a top end elevation view of the packaged umbrella taken on line 4—4 of FIG. 2;

FIG. 5 is a bottom end elevation view of the packaged umbrella.

The essential features of my new design reside in the sheath portion which is suspended by the umbrella's loop handle, as shown.

I claim:

The ornamental design for a packaged umbrella, as shown.
